UNITED STATES PATENT OFFICE.

EDSON O. SESSIONS, OF CHICAGO, ILLINOIS, ASSIGNOR TO THE CUTLER-HAMMER MFG. CO., OF MILWAUKEE, WISCONSIN, A CORPORATION OF WISCONSIN.

VAPORIZER.

1,215,879.

Specification of Letters Patent. Patented Feb. 13, 1917.

Application filed September 22, 1914. Serial No. 862,892.

To all whom it may concern:

Be it known that I, EDSON O. SESSIONS, a citizen of the United States, residing at Chicago, in the county of Cook and State of Illinois, have invented new and useful Improvements in Vaporizers, of which the following is a full, clear, concise, and exact description, reference being had to the accompanying drawing, forming a part of this specification.

10 This invention relates to vaporizers.

One of the objects of the invention is to provide an improved vaporizer in which heat may be applied to the quantity of fluid 15 to be vaporized without heating the whole body of fluid.

Another object of the invention is to provide a vaporizer in which the amount of fluid influenced by the heater may be regulated.

20 Still another object of the invention is to provide a vaporizer with means for regulating the rapidity and amount of vaporization.

25 Other objects and advantages will appear hereinafter.

The accompanying drawings illustrate an embodiment of the invention, and in said drawings—

30 Figure 1 is a partial cross-section and elevation of the vaporizer embodying the invention.

35 Fig. 2 is a partial cross-section and elevation of a modification of the structure shown in Fig. 1.

Fig. 3 is a partial cross-section and elevation of another modification.

The construction shown comprises in general a tank 1, containing a body of fluid 2, 40 having a heater 3 immersed therein.

The tank is provided with an inlet 4 controlled by a float valve 5 for maintaining a predetermined fluid level. An overflow 6 may also be employed. Obviously, any 45 other suitable means might be employed for maintaining the fluid at a predetermined level.

The heater 3, which also may be of any suitable form or type, is shown as comprising 50 a casing 7 of substantially triangular cross-section, containing standard electric heating units 8. This casing is supported

by a frame 9 in such a manner that the apex, or narrow part of the casing, projects upwardly. Located adjacent the sides of the 55 casing are the heater units 8. The exact location of said units and their shape may be adjusted to meet varying conditions. The location shown has been found desirable, since the heat is applied directly to the sides 60 of the casing where it is used efficiently.

When the heater is energized, the heat is transmitted directly from the sides of the casing to the fluid adjacent thereto. It has been found that in a heater such as shown, 65 the quantity of fluid heated is localized in a manner illustrated approximately by the shaded portions in Fig. 1. This localized and comparatively small quantity of fluid is very quickly heated with a minimum 70 amount of energy to a temperature sufficiently high to produce vaporization. Of course, as rapidly as the fluid adjacent the casing is vaporized, it is replaced by fluid from the main body. However, the heating 75 action as related to the whole body of fluid, is confined mainly to the shaded section, so that it is not necessary to heat a large quantity of fluid before vaporization is secured.

The amount of fluid which is acted upon 80 by the heater may be regulated by a variety of means, one of which consists in changing the level of the fluid surrounding the heater, as illustrated in Fig. 1. When the fluid is 85 at the highest level shown, or when the heater is totally immersed, the largest quantity of fluid is influenced by the heater. This is readily apparent from the shading in Fig. 1. The heating action is confined approximately to the fluid directly above the 90 sides of the heater. When the fluid level is high, all three of the shaded sections 10, 11, 12 will be heated. When the level 13 is used, the fluid represented by sections 11, 12, 95 is heated. As the level is further decreased, the amount of fluid influenced by the heater is correspondingly decreased, until at the level 14, only the small section 12 is heated. The rapidity and amount of vaporization 100 may thus be readily regulated.

The same results may be secured by using the construction shown in Fig. 2, in which the heater 3 is adjustably mounted, so that the heater may be raised and lowered in the

liquid, instead of changing the liquid level. Any suitable adjustable support for the heater may be used. In the construction shown, a member 15, attached to the bottom 5 of the heater, is arranged to coöperate with a worm gear 16, operated by connecting shafts 17 and 18 and a hand wheel 19. By turning the hand wheel, the heater may be raised or lowered and the same regulation 10 of vaporization secured as by changing the liquid level in the structure of Fig. 1.

Fig. 3 illustrates another means for securing regulation of the amount of fluid influenced by the heater. The heater casing 15 is made in sections hinged at the top, whereby the sides may be moved upwardly to the dotted line positions shown, thereby changing the angle of the heating surface and increasing the amount of fluid influenced by 20 the heater. The movement of the hinged portions is controlled by an adjustable screw 21, having threaded engagement with each hinged member in the manner shown.

While I have shown and described an embodiment of my invention, it should be understood that such embodiment is not to be construed as limiting the invention as defined by the spirit and scope of the appended claims.

Having described my invention, what I 30 claim and desire to secure by Letters Patent is:—

1. A vaporizer having a heater of substantially triangular cross-section arranged 35 in a body of liquid with the apex of the triangle above the surface of said liquid so that a relatively small amount of liquid is above the sides of the heater, whereby a portion of said liquid may be vaporized 40 without heating the whole body thereof.

2. A vaporizer having a heater of substantially triangular cross-section arranged 45 in a body of liquid with the apex of the triangle above the surface of said liquid whereby the relatively small amount of liquid above the sides of the heater may be vaporized without heating the whole body of liquid and means for regulating the 50 amount of liquid above the sides of the heater.

3. In a vaporizer, a receptacle, a body of liquid therein and an electric heater of substantially triangular cross-section arranged 55 in the receptacle with the apex of the triangle above the surface of the liquid whereby, when heat is applied to the heater, the relatively small amount of liquid above the sides of the heater is vaporized without heating the entire body of liquid.

4. A vaporizer having a heater enlarged 60 toward its base, said heater being arranged in a body of liquid with the top thereof above the surface of said liquid so that a relatively small amount of liquid is above 65 the sides of said heater whereby when heat

is applied the liquid may be quickly vaporized without heating the whole body thereof.

5. A vaporizer having a heater enlarged 70 toward its base and arranged in a body of liquid with the top of the heater above the surface of the liquid, whereby a relatively small quantity of liquid is above the sides of the heater and means for regulating the amount of fluid above said sides.

6. A vaporizer provided with a heater 75 casing having a relatively wide base and a relatively narrow top, the sides of said casing joining said base and top having means associated therewith for applying heat thereto, said casing being mounted in 80 a body of liquid with the top thereof above the surface of said liquid so that a relatively small amount of liquid is above the sides of the casing whereby vaporization is secured without heating the whole body of 85 liquid.

7. A vaporizer provided with a heater casing having a relatively wide base and a relatively narrow top, the sides of said casing joining said base and top having means 90 associated therewith for applying heat thereto, said casing being mounted in a body of liquid with the top thereof above the surface of said liquid so that a relatively small amount of liquid is above the sides of the 95 casing, whereby portions of said liquid are vaporized without heating the whole body of liquid and means for regulating the amount of liquid above the sides of the heater.

8. In combination in a vaporizer, a casing 100 of substantially triangular cross-section, electrical heating units in said casing adjacent the sides thereof, said casing being arranged in a body of liquid with the apex 105 of the casing above the surface of the liquid so that a relatively small amount of liquid is above the sides of the casing, whereby a small amount of said liquid may be vaporized without heating the whole body thereof. 110

9. In combination in a vaporizer, a casing 115 of substantially triangular cross-section, electrical heating units in said casing adjacent the sides thereof, said casing being arranged in a body of liquid with the apex 120 of the casing above the surface of the liquid so that a relatively small amount of liquid is above the sides of the casing whereby a small amount of said liquid may be vaporized without heating the whole body thereof and means for regulating the amount of liquid above the sides of the casing. 125

10. In combination in a vaporizer, a casing 130 of substantially triangular cross-section, electrical heating units in said casing adjacent the sides thereof, said casing being arranged in a body of liquid with the apex of the casing above the surface of the liquid so that a relatively small amount of liquid

is above the sides of the casing, whereby portions of said liquid may be vaporized without heating the whole body thereof and means for adjusting the angle of the sides 5 of said casing to regulate the amount of liquid influenced by said heater.

In witness whereof, I have hereunto sub-

scribed my name in the presence of two witnesses.

EDSON O. SESSIONS.
